UNITED STATES PATENT OFFICE.

RUDOLF OTTE, OF BRESLAU, GERMANY.

MAGNESIUM LAMP.

Application filed July 8, 1927, Serial No. 204,347, and in Germany February 16, 1926.

This invention relates to a magnesium lamp, and consists in the provision of a tubular handle having at one end a closure cap fitted with a clip, in which a piece of magnesium ribbon may be held for the purpose of ignition, the handle being used as a container for spare ribbons, which are cut into convenient lengths.

The cap may also be adapted to hold a reflector and a receptacle, or small ash-pan, in which to catch the falling magnesium.

The invention will be described more fully with reference to the accompanying drawing, in which

Fig. 1 represents a longitudinal section of the device in closed condition,

Fig. 2 being an elevation of the same in the condition for use.

Fig. 3 is another elevation of the device fitted with a reflector, which is shown in section.

Fig. 4 shows a bundle of ribbons made up to fit the container, and

Fig. 5 is a view showing the lamp in use, the reflector and the ash-pan or receptacle being shown in section.

The lamp is composed of a tube *a*, the ends of which are closed by telescopically inserted caps *b* and *c*. The cap *c* is reversible, and carries a clip *d*, in which a suitable length of magnesium ribbon *e* may be held while it burns, for example for the purpose of making photographic exposures, the tube being used as a handle.

At the same time the tube *a* is employed as a storage receptacle for the magnesium ribbons *e*, which may be tied into a bundle (as shown in Fig. 4) for insertion into the tube.

The lamp may be fitted with a reflector *f* having a central aperture whereby it fits on

the cap *c* so as to be held between a flange on the latter and the end of the tube *a*. A receptacle *h* in which to catch the falling ash may be connected to or made integrally with the reflector *f*.

A lamp of this type is extremely handy, and forms a valuable photographic accessory.

What I claim as new and desire to secure by Letters Patent is:

1. A magnesium lamp comprising a tubular handle, a reversible closure cap to the said handle, and a clip fitted on the said cap for holding a magnesium ribbon for ignition, the said handle being adapted to form a storage receptacle for convenient lengths of magnesium ribbon held in reserve.

2. A magnesium lamp comprising a tubular handle, a reversible closure cap to the said handle, a clip fitted on the said cap for holding a magnesium ribbon for ignition, and a reflector having an aperture allowing the same to be secured on the said cap between a flange on the latter and the end of the said handle, the said handle being adapted to form a storage receptacle for convenient lengths of magnesium ribbon held in reserve.

3. A magnesium lamp comprising a tubular handle, a reversible closure cap to the said handle, a clip fitted on the said cap for holding a magnesium ribbon for ignition, and a reflector in combination with an ash receiver, the said handle being adapted to form a storage receptacle for convenient lengths of magnesium ribbon held in reserve.

In testimony whereof I have affixed my signature.

RUDOLF OTTE.
